BUBBLER DRINKING FOUNTAIN OR SIMILAR
ARTICLE

William Martin, Arlington, Mass.

Application April 5, 1956, Serial No. 40,929

Term of patent 14 years

(Cl. D91—4)

Fig. 1 is a front elevational of a bubbler drinking fountain embodying my new design,

Fig. 2 is a side elevational view thereof, and

Fig. 3 is a top plan view thereof.

I claim:

The ornamental design for a bubbler drinking fountain or similar article, substantially as shown.
